UNITED STATES PATENT OFFICE

JOSEPH GUILLISSSEN, OF ANDERLECHT-BRUSSELS, BELGIUM; ASSIGNEE, BY MESNE ASSIGNMENTS, TO L'UNION CHIMIQUE BELGE, SOCIETE ANONYME, OF BRUSSELS, BELGIUM, A COMPANY OF BELGIUM

PROCESS FOR DRY DISTILLATION OF VINASSES UNDER REDUCED PRESSURE

No Drawing. Application filed November 8, 1923, Serial No. 673,549, and in Belgium December 15, 1923.

This invention relates to the production of nitrogenous combinations utilizable industrially and of acetone and acetonic oils.

The process which forms the subject of the present invention is adapted to recover almost the entire theoretical quantity of nitrogenous combinations utilizable industrially in a form which can readily be utilized and moreover it furnishes other products which will be designated hereafter.

The process consists in the pyrogenous distillation in closed retort and under reduced pressure, of the molasses or vinasse to which has been added a certain quantity of lime or other alkaline substance.

By vinasses I mean the residual liquid or liquids remaining from the fermentation and distillation of beet-sugar molasses.

The improved process provides:

1. A yield of nitrogen considerably higher than those of the previously known processes, reaching possibly 75 to 85 per cent of the theoretical quantity, and in a form which can readily be utilized.

2. A series of by-products not hitherto recovered industrially, such as acetone and nonnitrogenous tarry oil.

3. A considerable economy resulting from the fact that owing to the use of vacuum and the addition of lime, the temperature of distillation is materially lowered, which fact reduces the consumption of fuel and allows of employing apparatus of simple construction adapted to last a long time.

4. In the following description there are given two examples of the results obtained by treating according to the process indicated above firstly a de-sugared molasses, and secondly a molasses-distillery vinasse.

45 *First example.*—A molasses of 35° Beaumé desugared by means of strontium hydroxide and containing 2.1 per cent of total nitrogen, received an addition of lime amounting to from 50 to 100 per cent by weight of the desugared molasses treated and was then sub-

mitted to pyrogenous distillation at from 500 to 700° C. under an absolute pressure of about 60 millimetres of mercury.

The distillate contained a total quantity of combined and volatile nitrogen corresponding to 1.63 per cent of the molasses treated; namely 1.04 per cent in the form of ammonia and 0.59 per cent in the form of trimethylamine slightly mixed with higher amines.

There were also collected:

1. A volatile liquid distilling at 50 to 80° centigrade and containing mainly acetone mixed with a small quantity of aldehydes. This liquid represented about 1 per cent of the molasses treated.

2. A tar of less density than water, containing no nitrogen and representing about 10 per cent of the molasses treated.

3. In the residue of the distillation:

(a) Very light carbon, possessing an intense decolorizing power after suitable washing. This carbon represented about 7 per cent of the weight of the molasses treated.

(b) By lixiviation with water, it was easy to extract from the mineral residue a saline substance much cleaner than the salines derived from the ordinary calcination of vinasses and representing 13 per cent of the molasses treated.

Second example.—A molasses distillery vinasse of 35° Beaumé, containing 2.60 per cent of total nitrogen was subjected to the same treatment.

The nitrogen yield of the operation was about 2 per cent, in the form of ammonia and trimethylamine. The other products are comparable qualitatively and quantitatively with those of the preceding example.

It is obvious that the invention is in no way connected with the construction of the apparatus, the latter being constructed and arranged as deemed suitable with a view to obtaining the results set out above by the application of the process forming the subject of the invention.

Having now particularly described and ascertained the nature of my said invention and in what manner the same is to be performed, I declare that what I claim is:—

5 In the process of producing ammonia and amines utilizable commercially and acetone, subjecting vinasses to pyrogenous distillation under a pressure of approximately 60 m/m of mercury and in the presence of such an 10 amount of lime as is required to produce acetone.

In testimony whereof, I have signed my name to this specification at Brussels, Belgium this 24th day of October, 1923.

15 JOSEPH GUILLISSEN.
